UNITED STATES PATENT OFFICE.

LEO EHRLICH, OF ST. LOUIS, MISSOURI, ASSIGNOR, BY MESNE ASSIGNMENTS,
TO NATIONAL CASH REGISTER COMPANY, OF JERSEY CITY, NEW JERSEY.

MANUAL RECORDER OR AUTOGRAPHIC REGISTER.

SPECIFICATION forming part of Letters Patent No. 668,169, dated February 19, 1901.

Application filed December 5, 1895. Serial No. 571,116. (No model.)

To all whom it may concern:

Be it known that I, LEO EHRLICH, a citizen of the United States, residing at St. Louis, in the State of Missouri, have invented a certain 5 new and useful Improvement in Manual Recorders or Autographic Registers, of which the following is a description, reference being had to the accompanying drawings, forming part of this specification.

10 My invention relates to that class of manual recorders in which several paper strips are led over a writing-tablet and have manifolding material interposed between them above said tablet, by means of which the memo-
15 randa entered upon the upper strip is duplicated upon the lower strips, and in which the lower strip is led from the writing-tablet to a storage-compartment within the casing of the machine and there stored for future ref-
20 erence, while the upper strip or strips are led out of the machine and cut or torn off to form detached checks.

My invention relates more specifically to machines of the above class in which the 25 record-strip is folded back and forth upon itself in the storage-compartment of the machine and stored in that form instead of being wound upon a storage-reel, and the prin-
30 cipal feature of my invention relates to novel means for drawing forward the paper strips across the writing-tablet and storing the record-strip in compact folds within the machine. Its novelty will be hereinafter set forth, and specifically pointed out in the claims.

35 In the accompanying drawings, Figure 1 represents a perspective view of the complete machine; Fig. 2, a vertical section thereof just within the left-hand or near side wall in Fig. 1 looking toward the right of the ma-
40 chine; Fig. 3, a middle longitudinal vertical section; Fig. 4, a view looking at the front end of the machine, with the end plate of the casing removed and the semicircular hood at the top of the casing in section; Fig. 5, a view 45 corresponding to Fig. 4, with part of the folding mechanism removed; Fig. 6, a vertical section on the line 6-6 of Figs. 2 and 3; and Fig. 7, a view of the left-hand end of the machine corresponding to Fig. 3, but with the

pressure-frame shown in the act of folding 50 and storing the record-strip.

The same letters of reference are used to indicate identical parts in all the drawings.

The casing A of the machine may be of the usual or any suitable form, as seen in Fig. 1, 55 consisting in this instance of a bottom plate, side walls, end walls, one of which, at the right-hand end of the machine, is hinged, so that it may be swung outward and downward and give access to the interior of the casing, 60 and a removable lid or top, the hinged end wall and lid being secured in position by a suitable lock.

Near its forward end the top of the casing is provided with a rectangular opening, as 65 usual, beneath which is mounted the trans-
verse plate or writing-tablet B, Fig. 3, which is supported at its opposite edges upon the side walls of the casing. At its left edge this plate has formed integral with it a receptacle 70 C, Figs. 2 and 6, for the reception of the roll of carbon strips or other manifolding mate-
rial, which are led across the plate B to the right-hand edge thereof between the several strips of paper hereinafter referred to, as 75 usual.

In the present instance three strips of paper are employed in the machine, one of which serves as a record-strip and is stored within the machine, while the other two serve as 80 check-strips and are delivered from the machine and torn off into checks. These three strips are carried in supply-rolls D, E, and F, which rest upon the bottom plate of the casing at the right-hand end of the machine, as 85 seen in Figs. 2 and 3, the rolls being held in line with each other and kept from lateral displacement by narrow vertical plates G G, projecting upward from the bottom plate of the casing at their opposite sides. When the 90 supply-rolls of the paper strips in machines of this class are supported upon spindles and arranged to turn thereon, as is generally the case, suitable friction or tension devices have to be applied to them to preserve the proper 95 tension upon the strips as they are drawn forward to the writing-tablet. In my machine the rolls rest and are supported upon the bot-

tom plate of the casing, the strip from the roll D being led beneath the rolls E and F, which latter therefore rest upon it, while the strip from the roll E is led beneath the roll F, so that the latter rests both upon it and upon the strip from the roll D. All three of the strips are led beneath a guide rod or roller H at the lower right-hand corner of the machine, thence upward or over a second guide rod or roller I at the upper right-hand corner of the machine, and thence forward to the left over the writing-tablet. As the strips are drawn forward the friction of the lower one against the bottom of the casing as the others rest upon it produces a tension upon the strips, which holds them taut between the supply-rolls and writing-tablet. So, too, the drawing forward of the strips turns the three rolls D, E, and F in the direction of the arrows, from which it will be seen that the adjacent rolls bearing against each other turn in opposite directions at their points of contact; and thus each offers a resistance to the turning of the other, which, in addition to the weight of the rolls upon the strips, produces a further tension upon the strips. The drawing forward of the strips maintains the rolls in the right-hand end of the machine; but a suitable stop may be provided at the left of the roll D, if desired, to prevent it rolling to the left out of position in case the right-hand end of the machine should be tilted upward. I am aware that it has heretofore been proposed in machines of this character to mount the series of rolls of paper strips upon spindles and support the ends of the latter in inclined slots, permitting the rolls to bear against each other and offer resistance to the withdrawal of the strips; but so far as I am aware I am the first to arrange the rolls in the manner which I have shown and described, resting directly upon a horizontal surface with the strip from each roll led beneath the rolls in front of it, so that the rolls preserve a tension upon the strips in the manner explained. From the writing-tablet the three strips pass forward between a pair of feed-rollers J K, the former being a large roller, whose length is nearly equal to the width of the casing or at least as wide or wider than the paper strips, while the roller K is in the present instance a comparatively small and short one fastened upon a shaft L and bearing upon the upper side of the roller J, at the middle of the latter. The two rollers are geared together by means of a gear M, fast upon the end of the roller J and meshing with a pinion N upon the shaft L. The roller J is loosely mounted upon a rotary shaft O, suitably journaled in the opposite side walls of the casing of the machine and projecting at its left-hand end through the wall of the casing and having fastened upon it an operating-handle P, provided with a grasping-knob Q. The roller J being loose upon the shaft O the handle and shaft are free to turn independently of the roller; but

they are connected together, so as to cause the shaft to carry the roller with it in one direction by means of a pawl R, Fig. 2, pivoted to and carried by an arm S, fast upon the shaft O and spring-pressed against the periphery of the hub of the roller or gear M upon the end of the roller; said hub having in it a notch with which the pawl co-operates to turn the roller when the shaft and pawl are turned in a forward direction. The result of this arrangement is that when the operating-handle and shaft are given a forward revolution the three paper strips will be drawn forward by the feed-rollers, the two upper strips passing out of the casing through a transverse slot or opening between the upper edge of the forward end wall of the casing and the lower edge of the hood T, formed at the forward end of the top plate of the casing to accommodate the upper feed-roller, while the lower one of the three strips passes downward between the roller J and end wall of the casing into the front end of the machine, where it is stored in a manner to be presently described. When the operating-handle and shaft O are turned backward to normal position, the pawl R slips idly backward over the hub of the roller J and reengages the notch therein when it comes to normal position. For the purpose of limiting this forward-and-backward movement of the operating-handle and shaft O there is hung loosely upon the shaft, at the right of the arm S in Figs. 4 and 2, a two-armed plate, Fig. 2, whose opposite arms co-operate with a fixed stud V, projecting inward from the side wall of the casing. The plate U is free to swing back and forth between the points of contact of its two arms with said stud. The arm S, which is fast upon the shaft O and carries the pawl R, has upon its side adjacent the plate U a stud or pin W, Fig. 2, which projects into the vertical plane of the plate U. When the operating-handle and shaft O are turned forward, the stud W will contact with the front edge of the plate U as the parts approach a complete revolution and will then carry the plate U with them until it is arrested by contact of its forward arm with the stop V. When the handle and shaft are turned backward, the pin W will likewise contact with the opposite edge of the plate U as the parts approach normal position and carry it forward to the position shown in Fig. 2, where its right-hand arm contacts with the stop V and arrests the parts in normal position. The limit of movement thus given the roller J is just sufficient to draw forward the desired lengths of the paper strips at each operation of the machine. As the record-strip passes downward between the roller J and end wall of the casing it is guided from lateral displacement by two curved plates X X, Figs. 2 to 5, secured to the opposite ends of a transverse block or bar Y, which is secured to the forward side of the upper cross bar or plate of a rectangular frame Z, Fig. 5, which is rigidly

secured in vertical position beneath the roller J, being bolted or screwed at its lower end to the bottom plate of the casing at a. In addition to being held from lateral displacement 5 by means of the guide-plates X X the paper strip as it is fed downward from the roller J is directed to the right toward the open frame Z by a curved plate or series of fingers A', depending from the under side of the curved 10 end wall of the casing and rigidly secured to or formed integral therewith. The result of these arrangements is that the paper strip is directed downward and to the right and hangs in front of the rectangular opening in the frame Z. Extending longitudinally of the machine from the frame Z at its left-hand end to nearly its right-hand end are four rods B', Figs. 2, 3, and 6. These rods at their left-hand or forward ends are rigidly secured to 20 the four corners of the rectangular frame Z, while at their right-hand ends they are rigidly secured to vertical ribs C', formed upon the inner faces of the side walls of the casing. About midway of their length the rods also 25 pass through enlarged openings in a pair of similar ribs D', formed on the side walls of the casing. Mounted upon these four rods near their left-hand ends, so as to slide freely backward and forward, is a vertical plate or 30 platen E', while surrounding each rod and confined between said plate and the support of the rod at its extreme right-hand end is a coiled spring, the four springs bearing against the four corners of the plate E' and pressing 35 it forward to the left and tending to hold it against the rear side of the frame Z. As a further guide for the plate E' its lower edge is provided with notches which fit over guide- 40 rods F', secured at their front ends to the lower cross-bar of the frame Z and extending some distance to the right along the bottom 45 of the casing. The plate E' has secured or formed upon its rear side a thumb-piece G', by which it may be grasped and pulled toward the right against the resistance of the springs 50 for a purpose hereinafter explained.

As seen in Fig. 5, the upper transverse bar or plate of the frame Z has secured to or formed integral with it a depending plate H' 55 somewhat shorter than the width of the rectangular opening of the frame, so that a space is left at each end of the plate H', between it and the adjacent vertical side bar of the frame. There is also secured in the lower part of the frame a transverse rod I', whose opposite ends are fastened to the vertical side bars of the frame. It will now be seen that if with the plate E' pressed up against the rear side of the frame Z and with the paper strip hanging 60 down in front of the rectangular opening in said frame, as indicated by the dotted lines in Figs. 2 and 3, said strip be pressed through the opening against the plate E' by means of a plate closely fitting the opening in the frame 65 and caught between the plate H' and plate E' at the upper side of the opening and between the plate E' and rod I' at the lower side of the

opening the successive lengths of the strip advanced by the feed-rollers may be thus stored away in reverse folds between the frame Z and plate E'. The means for so pressing the paper through the opening in the frame and causing it to be caught and held between the plate E' and the plate H' and rod I' may be next described.

Loosely hung at their upper ends upon the shaft O, just within the opposite side walls of the casing, Fig. 4, are two downwardly-extending curved side arms or plates J', Figs. 2 and 3, whose lower ends are rigidly secured 70 to the opposite ends of a pressure-plate K' of rectangular shape and adapted to closely fit, but be capable of passing through the opening in the frame Z or the space between the plate H' at the upper side and the rod I' at 75 the lower side thereof. Pivoted upon bosses upon the inner faces of the side walls of the casing in line with each other and beneath the axial shaft O of the feed-roller J are two levers L' L', whose lower ends are provided 80 with studs M', passing through slots in links N', whose left-hand ends are pivotally connected to the respective side arms J', which carry the pressure-plate K'. The upper end of the lever L' at the left-hand side of the machine, Fig. 2, (right-hand side Figs. 4 and 5,) 85 stands in the path of a stud O' upon the inner side of the arm S, which is fast upon the shaft O, as heretofore described, while the upper end of the lever L' at the opposite side of the machine stands in the path of a stud O² upon a similar arm S², fast upon that end of the shaft O. When the operating-handle and shaft O' are given a forward revolution, the studs O' O² will contact with the upper ends 90 of the levers L' L' as the parts approach the end of the revolution and will ride over said levers and pass them, the lower ends of the levers being free to swing toward the left, the studs M' playing idly in the slots in the 95 links N', and after the studs O' O² have cleared the upper ends of the levers the latter will swing back to normal position, with their upper ends in the return-path of the studs O' O². When the operating-handle is now given 100 a backward revolution to normal position, the studs will again contact with the upper ends of the levers L' and will force them forward, throwing their lower ends rearward to the right and causing them to pull the arms 105 J' and pressure-plate K' in that direction and carry said plate through the opening in the frame Z, Fig. 7. As soon as such studs clear the upper ends of the levers L' the spring K² will return the frame K' and the levers to the 110 normal position shown in the drawings. The movement thus imparted to the pressure-plate K' will cause it to carry the paper strips through the opening in the frame Z and press it against the plate E'.

Arranged beneath the path of travel of the plate K', in front of the frame Z, is a block P', extending transversely across the machine and having its upper side curved in the

are of a circle approximating that described by the lower edge of the plate K'. The lower edge of the plate in its forward-and-backward movement travels a short distance above the curved upper surface of this block I' and is provided with a rearwardly-projecting flange K³. With the paper strip in the position indicated by the dotted lines in Fig. 3 when the plate K' is swung to the right the two sides of the depending loop of the paper strip will be pressed together and the lower edge of the loop or fold will be caught between the lower edge of the plate K' and its flange K³ and the upper surface of the block I' and be bent to the left under the lower edge of the plate as the latter approaches the rod I', and as the lower edge of the plate and its flange K³ pass to the left over the rod I', as shown in Fig. 7, the lower end or edge of the fold projecting below the plate will be pressed against the rod I' by the lower edge of the plate and then by the flange K³, so that a sharply-defined fold will be formed, as shown in Fig. 3. As the parts reach the position shown in Fig. 7 the lower edge of the fold, bent to the left under the plate and flange K³, will clear the rod I' and spring downward to the position shown, so as to catch against and be held by the rod I' when the plate K' is swung to the left again, as in Fig. 3. At the upper edge of the plate K' the paper strip will be simply pressed through the opening and against the plate E', so that in order to cause the upper edge of the fold to be caught and held between the plate E' and the plate H' of the frame Z it is necessary to provide means for tucking the fold up behind the plate H' and between it and the plate E'. The means provided for this purpose consist of a rod Q', Fig. 4, secured at its opposite ends to the lower ends of a pair of bell-crank arms R', pivoted to the side arms J', which support the plate K', Fig. 3, springs S', connected to the arms R' and to the arms J', yieldingly holding the rod Q' and bell-crank arms in normal position. The upper rearwardly-projecting arms of the bell-cranks are provided with studs T', which are adapted when the arms J' and plate K' are swung to the right to contact with plates U', projecting forward from the opposite ends of the plate Y, Figs. 2 to 5. The studs T' contact with the plates U' before the arms J' and plate K' complete their movement to the right, so that as they finally complete their movement the bell-cranks are rocked upon their pivots and the rod Q' thrown upward behind the plate J', as shown in Fig. 7, the lower arms of the bell-cranks passing upward along the opposite ends of the plate H', in the spaces between its ends and the side arms of the frame Z, heretofore referred to. When the rod Q' is thrown upward to this position, it carries the upper fold of the paper strip with it, and as the rod recedes at the beginning of the backward movement of the pressure-plate K' the plate E', pressed forward by the springs, catches the fold of the strip and con-

fines it between itself and the plate H'. At each operation of the machine the portion of the record-strip advanced by the feed-rollers is in this manner folded into reverse folds and confined between the yielding platen E' and the plate H' and rod I' of the frame Z, and as the operations of the machine continue the folds of the strip pressed against the platen E' gradually force the same backward against the resistance of the springs. When it is desired to remove the stored record-strip from the machine, it is only necessary to sever the strip by inserting a knife through the slot where the check-strips emerge from the machine and drawing it across the roller J from end to end, the roller being provided with a longitudinal groove c to facilitate the cutting, and then pull the platen E' backward by means of the thumb-piece G, whereupon the stored strip pressed upon the platen will be released and may be readily removed, the unfolded end of the strip where it was severed from the main strip being drawn out through the opening in the frame Z with the folded portion of the strip. For the purpose of permitting access to the platen E' for thus removing the stored strip the left-hand side wall of the casing is provided with an opening at V', Fig. 1, which opening may be normally closed by any suitable slide or door secured by a lock.

Regarding the frame Z, through the opening in which the paper strip is pressed, it will be understood that the only parts of it essential to the folding and storing operations are the plate H' and rod I', the remainder of the frame serving merely to support those parts. So, too, it will be understood that the lower cross-bar of the frame might be wide enough and extend high enough for its upper edge to serve the purpose of the rod I' and the latter be dispensed with, the plate H' and rod I' being simply fixed cross-pieces to co-operate with the upper and lower edges of the plate K' to fold the strip and with the platen E' to retain the folds after they have been made.

I am aware, as indicated at the beginning of this specification, that it is old in machines of this class to draw the paper strip forward from the supply-rolls by means of a pair of feed-rollers, leading it across a writing-tablet between the supply-rolls and feed-rollers, and to fold the record-strip back and forth in reverse folds and store it in that form upon a spring-pressed platen or supporting-plate within the storage-compartment of the machine, as shown and described, for instance, in the patent to Bentel, No. 438,835, and that it has been proposed to actuate the folding mechanism in such machines by the same handle which operates the feed-rollers; but so far as I am aware I am the first in the art to employ in a machine of this character a folding mechanism resembling, either in construction or mode of operation, that which I have illustrated and described, and my invention is therefore not restricted to details of

construction, but contemplates, broadly, the combinations and arrangements of parts and the modes of operation set forth in my respective claims.

5. Having thus fully described my invention, I claim—

1. In an autographic register, the combination with the casing, of the supply-rolls carrying the paper strip, resting on the bottom 10 of the casing, the strip from each roll passing under the roll or rolls in advance of it, whereby when the strips are drawn forward the friction of the lowermost strip against the bottom of the casing will produce tension on 15 the strip, and hold them taut; substantially as described.
2. In an autographic register, the combination with the casing, of the supply-rolls carrying the paper strip resting on the bottom 20 of the casing, side by side in direct contact with each other, the strips from each roll passing under the roll or rolls in advance of it, whereby the withdrawal of the strip causes the rolls to turn in opposite directions and 25 each to offer frictional resistance to the turning of the other, keeping the strip taut, the weight of the rolls on the strip also adding to the tension on the strip; substantially as described.
3. In an autographic register, the combination of a pair of feed-rollers for drawing the paper strips forward across the writing-tablet, an operating handle or crank having a forward-and-backward movement, a connection between said handle and one of the feed-rollers for causing the handle to turn the roller forward with it but permit the roller to remain at rest while the handle is moved backward to normal position, and a 40 folding mechanism actuated by the operating-handle at its backward stroke to fold the record-strip and store it in the storage-compartment of the machine.
4. In an autographic register, the combination of a pair of feed-rollers for drawing the paper strips forward across the writing-tablet, an operating handle or crank having a forward-and-backward movement, a connection between said handle and one of the feed-rollers for causing the handle to turn the roller forward with it but permit the roller to remain at rest while the handle is moved backward to normal position, a yielding platen or support in the storage-compartment of the machine, and means actuated by the handle at its backward stroke for pressing the record-strip in folds against said platen or support, whereby the forward movement of the operating-handle advances the paper 50 strips and its backward movement stores the record-strip in reverse folds in the storage-compartment of the machine.
5. In an autographic register, the combination of a pair of feed-rollers for drawing the paper strips forward across the writing-tablet, an operating-handle for turning said rollers, two horizontal fixed cross-pieces be- 55 neath the feed-rollers, one above the other and forming a rectangular opening between them, in front of which opening the paper record-strip hangs as it is advanced by the feed-rollers, and a pressure plate or frame actuated by the operating-handle for pressing the depending fold of the strip through said opening, substantially as and for the 60 purpose described.
6. In an autographic register, the combination of a pair of feed-rollers for drawing the paper strips forward across the writing-tablet, an operating-handle for turning said rollers, two horizontal fixed cross-pieces beneath the feed-rollers, one above the other, and forming a rectangular opening between them, in front of which opening the paper record-strip hangs as it is advanced by the feed-rollers, a yielding platen or support behind said opening, and a pressure plate or frame actuated by the operating-handle for pressing the depending fold of the paper strip through said opening and against the yielding platen or support, substantially as and for the 65 purpose described.
7. In an autographic register, the combination of a pair of feed-rollers for drawing the paper strips forward across the writing-tablet, an operating-handle for turning said rollers, two horizontal fixed cross-pieces beneath the feed-rollers, one above the other and forming a rectangular opening between them, in front of which opening the paper record-strip hangs as it is advanced by the feed-rollers, a vertical plate arranged behind said opening and movable horizontally toward and from the opening, springs pressing said plate toward the opening, and a pressure 70 plate or frame actuated by the operating-handle for pressing the depending fold of the paper strip through said opening and against said plate, substantially as described.
8. In an autographic register, the combination of a pair of feed-rollers for drawing the paper strips forward across the writing-tablet, an operating-handle for turning said rollers, two horizontal fixed cross-pieces beneath the feed-rollers, one above the other and forming a rectangular opening between them, in front of which opening the paper record-strip hangs as it is advanced by the feed-rollers, a pressure plate or frame actuated by the operating-handle for pressing the depending fold of the paper strip through said opening, and means co-operating with the pressure plate or frame for tucking the upper edge of the fold of the strip up behind the fixed cross-piece at the upper side of the 80 opening, substantially as described.
9. In an autographic register, the combination of a pair of feed-rollers for drawing the paper strip forward across the writing-tablet, an operating-handle for turning said rollers, two horizontal fixed cross-pieces beneath the feed-rollers, one above the other and forming a rectangular opening between them, in front of which opening the paper record- 85

strip hangs as it is advanced by the feed-rollers, a yielding platen or support behind said opening, a pressure plate or arm actuated by the operating - handle for pressing the depending folds of the paper strip through said opening, and against the yielding platen, and means for tucking the upper fold of the strip up between the yielding platen and the cross-piece at the upper side of the opening, substantially as described.

10. In an autographic register, the combination of a pair of feed-rollers for drawing the paper strips forward across the writing-tablet, an operating-handle for turning said rollers, two horizontal fixed cross-pieces beneath the feed - rollers, one above the other and forming a rectangular opening between them, in front of which opening the paper record-strip hangs as it is advanced by the feed-rollers, a yielding platen or support behind said opening, a pressure plate or arm actuated by the operating - handle for pressing the depending folds of the paper strip through said opening, and against the yielding platen, and a transverse rod suitably supported and actuated and operating to tuck the upper fold of the strip up between the yielding platen and the cross-piece at the upper side of the opening, substantially as described.

11. In an autographic register, the combination of a pair of feed-rollers for drawing the paper strips forward across the writing-tablet, an operating-handle for turning said rollers, two horizontal fixed cross-pieces beneath the feed-rollers, one above the other and forming a rectangular opening between them, in front of which opening the paper record-strip hangs as it is advanced by the feed-rollers, the swinging pressure-plate K' carried by the side arms J', means intermediate said pressure-plate and the operating-handle for causing the latter to swing the plate rearward through the opening above referred to, the spring K² for resetting the plate, the transverse rod Q' carried by the bell-crank arms E' pivoted upon the side arms J', and the abutments U' coöperating with the upper arms of the bell-cranks to swing the rod Q' upward behind the upper cross-piece at the end of the rearward movement of the pressure-plate K' and arms J', substantially as and for the purpose described.

12. In an autographic register, the combination of the feed-rollers J K for drawing the paper strips forward over the writing-tablet, the shaft O' upon which the roller J is loosely mounted, the operating-handle P fast upon said shaft, a connection between said shaft and the roller J for causing the shaft to carry the roller with it in a forward direction, but not in a backward one, the fixed cross piece or plate H' beneath the roller J and the fixed cross piece or rod I' below the plate H', with the open space between them, the vertical plate E' suitably supported behind this open space and the springs pressing it forward, the swinging pressure-plate K' carried by the side

arms J', the spring K² for yieldingly holding said plate in normal position, the levers L' L' connected at their lower ends with the side arms J' by the slotted links N', and the arms S' and S² fast upon the shaft O at the opposite ends of the roller J and coöperating with the upper ends of the levers L', in the manner and for the purpose described. 75

13. In an autographic register, the combination of the fixed cross-pieces H' I' having the open space between them, the yielding plate E' behind said open space, the swinging arms J' carrying the pressure-plate K' adapted to pass through said opening, the spring K² for holding the plate K' and arms J' in normal position, means for swinging them rearward to cause said plate K' to pass through the opening between the cross-pieces H' and I', 85 the bell-cranks R' pivoted to the side arms J', the rod Q' carried by the lower arms of the bell-cranks, the spring or springs S' for holding the bell-cranks and arm Q' in normal position relatively to the arms J', and the fixed 90 plates or abutments U' coöperating with the upper arms of the bell-cranks to throw their lower arms upward at the opposite ends of the cross-piece H' and carry the rod Q' upward behind said cross-piece, substantially as 95 and for the purpose described.

14. In the folding mechanism of an autographic register, the combination of the fixed cross-pieces H' and I', and the reciprocating pressure-plate K' adapted to pass through 100 the opening between said cross-pieces and provided with the flange K³ coöperating with the lower cross-piece in the manner and for the purpose described.

15. In the folding mechanism of an autographic register, the combination of the fixed cross-pieces H' and I', the reciprocating pressure-plate K' adapted to pass through the opening between said cross-pieces, and the block P' arranged in front of the lower cross-piece and coöperating with the lower edge of the plate K' in the manner and for the purpose described. 105

16. In the folding mechanism of an autographic register, the combination of the fixed cross-pieces H' and I', the reciprocating pressure-plate K' adapted to pass through the opening between said cross-pieces and provided with the flange K³ coöperating with the lower cross-piece, and the block P' arranged 110 in front of the lower cross-piece and coöperating with the lower edge of the plate K' and its flange K³ in the manner and for the purpose described. 115

17. In the folding mechanism of an autographic register, the combination of the fixed cross-pieces H' and I', the swinging pressure-plate K' having the flange K³ along its lower edge and adapted to pass through the opening between said cross-pieces, and the block 120 P' arranged in front of the lower cross-piece and having its upper face curved in the arc of a circle conforming to that described by the lower end of the swinging plate K', and 125

coöperating with the latter and its flange K³ in the manner and for the purpose described.

18. In an autographic register, the combination of the feed-rollers J K, the shaft O upon which the roller J is mounted, a handle for turning said shaft forward and backward, the plate U loosely hung upon the shaft O and coöperating with the fixed stop V, and the arm S fast upon the shaft O and having the stud

W coöperating with the plate U and carrying to the pawl R coöperating with a notch or projection on the roller J, as and for the purpose described.

LEO EHRLICH.
